FIG. 1 is a front view of the first image in a sequence of a display screen or portion thereof with transitional graphical user interface showing our new design;
FIG. 2 is the second image thereof;
FIG. 3 is the third image thereof; and,
FIG. 4 is the fourth image thereof.

The outermost broken lines in the figures illustrate a display screen or portion thereof, and form no part of the claimed design. The remaining dashed broken lines in the drawings illustrate portions of the graphical user interface that form no part of the claimed design.

The appearance of the transitional image sequentially transitions between the images shown in FIGS. 1-4. The process or period in which one image transitions to another image forms no part of the claimed design.
